UNITED STATES PATENT OFFICE.

GEORGE H. GREGORY, OF MOUNT CARMEL, ILLINOIS.

FURNACE-DOOR-OPERATING DEVICE.

1,091,060.

Specification of Letters Patent. Patented Mar. 24, 1914.

Application filed May 22, 1913. Serial No. 769,145.

To all whom it may concern:

Be it known that I, GEORGE H. GREGORY, a citizen of the United States, residing at Mount Carmel, in the county of Wabash 5 and State of Illinois, have invented certain new and useful Improvements in Furnace-Door-Operating Devices, of which the following is a specification.

My invention relates to improvements in 10 furnace door operating devices, the primary object being to provide a generally improved furnace door and means for operating the same which may be readily applied in front of the feed door openings of furnaces, the 15 present embodiment being particularly designed and adapted for use in connection with railroad locomotives, and providing means whereby the fire door may be readily opened by the foot of the fireman through 20 the medium of a foot lever, and after being opened will be automatically closed when the pressure on the foot lever is removed.

With the above mentioned and other ends in view, the invention consists in the novel 25 construction, arrangement, and combination of parts, hereinafter described, illustrated in one of its embodiments in the accompanying drawings, and particularly pointed out in the appended claims.

Referring to the drawings, forming a part 30 of this specification, Figure 1, is a perspective view of the improved furnace door, together with the attaching frame and door operating mechanism carried by the latter. 35 Fig. 2, a fragmentary view of a modified form of door operating bell cranks or levers.

Similar numerals of reference designate like parts throughout all the figures of the drawings.

The improved furnace door and door operating mechanism comprises a frame 1, adapted to be removably and adjustably secured to the front of the furnace through 40 the medium of cap screws or bolts 2, passing through slots 1^a, in the upper and lower members of the door frame and into suitable threaded openings of the furnace wall above and below the feed door opening thereof.

The sides of the frame 1, are provided 45 with vertically extending guide members 3, forming guide-ways or grooves 3^a, adapted to receive and contain the ends of a pair of vertically movable door members 4. The 50 guide members 3, are preferably secured to the sides of the frame 1, by means of bolts

3^b, and one of the guide members 3, is preferably provided with a side extension or bearing plate 3^c, to form a support or bearing for the door operating bell cranks or 60 lever members, hereinafter described.

The vertically movable slidably mounted door members 4, are provided at their central front or face sides with bearing members or projections 4^a, in the present instance, in the form of headed bearing pins 65 removably mounted in the door members.

As a means for simultaneously operating or actuating the door members 4, from and toward each other or in their opening and closing movements, a pair of bell cranks or door operating crank arms 5, are pivotally mounted upon the side extension or bearing plate 3^c, through the medium of bearing bolts 6, said bell cranks having their shorter 70 arms 5^a, extending toward and operatively connected to each other, the main or longer arm or lever members 5, being provided at their outer ends with guide slots 5^b, receiving and taking over the bearing members 75 or pins 4^a.

As a means for further supporting the bearing bolts 6, and maintaining the short arms 5^a, of the bell cranks 5, in proper relative position, a guide or keeper plate 7, is 80 removably secured through the medium of the bearing bolts 6.

From the above description it will be understood that the connection between the shorter arms 5^a, should be such that when 90 one of the arms 5, is moved in one direction, the opposite or opposing arm 5, will be moved in the other, so that the door members 4, connected thereto will be simultaneously actuated toward and from each other, 95 and as a means for automatically returning the doors and the attached parts of the foot operating mechanism, hereinafter described, to their closed position, the upper door member 4, is preferably made of such weight 100 over and above the weight of the lower door member and the operative weight of the foot lever mechanism as to overcome such weight and return the parts to their closed position, as shown in Fig. 1, of the drawings. 105

As a means for actuating the lower bell crank, a foot lever 8, is pivotally secured at one side of the door frame 1, by means of a pivot bolt 8^a, said foot lever being connected to the lower bell crank arm 5, through 110 the medium of a connecting link 9, the latter being adjustably connected at its ends to

bearing clips or brackets 10, through the medium of adjusting nuts 9^a, whereby the throw of the foot lever 8, may be regulated.

In the modified form of bell crank shown 5 in Fig. 2, the short arms 5^a, are connected to each other through a bearing head 5^c, on one arm and a bifurcated head 5^d, on the other. In this modified form of bell cranks the lower crank is provided with an extension 5^e, adapted to carry a weight 11, adjustably mounted on the extended portion 5^e, in lieu of increasing the weight of the upper door member 4, as above described in connection with the form of bell cranks shown 10 in Fig. 1.

From the foregoing description, taken in connection with the accompanying drawings, the operation and advantages of my invention will be readily understood.

20 Having thus described one of the embodiments of my invention, what I claim and desire to secure by Letters Patent is,—

1. In a furnace-door operating device, the combination with a frame provided with 25 vertical guide-ways, door members slidably mounted therein, the upper door being weighted to overbalance the weight of the lower door and the operating attachments and bell-cranks pivotally mounted at one 30 side of said frame, one pair of arms being operatively connected in one direction by the weight of said upper door only and the other pair of arms being provided at the ends with slot openings; of guide bearing pins 35 extending through said slot openings and carried by the front central portions of said door members, a guide plate mounted in front of said first mentioned pair of arms, and a foot lever pivotally carried at one 40 side of said frame and operatively connected to one of said bell-cranks.

2. A furnace-door operating device, comprising a door frame having vertical guide members one of said guide members being

provided with a bearing plate, vertically 45 movable door members slidably mounted therein and provided at their central front portions with bearing pins, bell-cranks having their shorter arms operatively connected to each other by the weight of the upper 50 door only and having their longer arms provided with slots taking over said bearing pins, a keeper plate mounted in front of said shorter arms of said bell-cranks, bearing bolts extending through said keeper and bearing plates and said bell-cranks, a foot lever pivotally mounted at one side of said door frame and beneath said bell-cranks, and a connecting link adjustably connected to said foot lever and the lower of said bell-cranks. 60

3. A furnace door operating device, comprising a door frame, vertical door guide members, one of said members being provided with a vertically extending bearing plate, door members mounted in said guide members the upper door member being weighted to overbalance the weight of the lower door member and operative weight of the door operating attachments, bell-cranks having one pair of arms disposed in front of 70 said vertically extending bearing plate and held in contact with each other by said weighted upper door only and the other pair of arms extending in front of and pivotally connected to the central portions of said door members, a keeper plate mounted in front of said first mentioned arms of said bell-cranks, bearing bolts extending through the latter and said keeper and bearing plates, an operating foot lever, and a connecting link between the latter and one of 75 said bell-cranks. 80

In testimony whereof I have affixed my signature in presence of two witnesses.

GEORGE H. GREGORY.
